DESIGN FOR A HOUSING FOR GARBAGE OR SEWAGE TRITURATORS AND THE LIKE

William B. Marshall, Milwaukee, Wis., assignor
to Chain Belt Company, Milwaukee, Wis., a cor-
poration of Wisconsin

Application October 15, 1937, Serial No. 72,218

Term of patent 14 years

To all whom it may concern:

Be it known that I, William B. Marshall, a citizen of the United States, residing at Milwaukee, in the county of Milwaukee and State of Wisconsin, have invented a new, original, and ornamental Design for Housings for Garbage or Sewage Triturators and the like, of which the following is a specification, reference being had to the accompanying drawing, forming part thereof.

In the drawing:

Fig. 1 is a perspective view of a housing for garbage or sewage triturators and the like, showing my new design; and

Fig. 2 is a plan view thereof.

I claim:

The ornamental design for a housing for garbage or sewage triturators and the like, as shown.

WILLIAM B. MARSHALL.
